Lester D. Behrman

UNITED STATES PATENT OFFICE.

MARCUS B. BEHRMAN, OF NEW YORK, N. Y., ASSIGNOR TO LOX SEAL CORPORATION, A CORPORATION OF NEW YORK.

TAG-FASTENER.

1,308,771.

Specification of Letters Patent.

Patented July 8, 1919.

Application filed May 26, 1917. Serial No. 171,117.

To all whom it may concern:

Be it known that I, MARCUS B. BEHRMAN, a citizen of the United States, residing at the city, county, and State of New York, 5 have invented certain new and useful Improvements in Tag-Fasteners, of which the following is a specification.

My invention relates to tag-fasteners, and its principal purpose is to provide a device of simple, effective and inexpensive construction for securing a tag to an article of wearing apparel, or other object, in such manner that the tag can not be removed without mutilating the device or cutting the 15 cord whereby it is fastened to the object.

To these ends my invention consists in the novel features of construction, combination and arrangement of parts herein described and particularly pointed out in the 20 claims.

In the accompanying drawings illustrating a preferred embodiment of the invention, Figure 1 is a perspective view of the fastener attached to an object; Fig. 2 is a 25 cross-section on the longitudinal center line, and Fig. 3 is a view of the cord detached from the fastener.

Referring to the drawings, T indicates a tag, F the fastener, C the cord for securing 30 the fastener to an object, and O the object to which the tag-fastener is applied, which, in the present instance, is represented as a fragment of a garment having a button hole through which the cord is secured.

35 In the particular embodiment of the invention, as illustrated herein, the fastener F is made of a single piece of sheet metal which is bent in substantially U-shape to form a front wall 1, a rear wall 2 and two tapered 40 side walls 3-3. Two small apertures 4-4 are formed through the bent upper end of the fastener for receiving the tips 5-5 of the cord C.

The lower portions of the front and rear 45 walls 1 and 2 form a clip between which the marginal edge of the tag T is clamped. A rivet 6 is preferably fixed through the parts to permanently attach the tag to the fastener.

50 A cord C is provided at its ends with rigid tips 5-5, preferably made of stamped sheet metal, which tips are longer than the diameter or greatest width of the apertures and are applied so as to extend at right 55 angles to the axis of the cord, when the

latter is stretched in a straight line, as shown in Fig. 3.

The fastener F performs two principal functions, namely, it serves as a means for securing the tips of the cord C to prevent 60 removal thereof when inserted therein, and for engaging and holding the tag T. The body of the fastener may be made in a variety of different shapes and forms, but in whatsoever form it is constructed it will 65 be provided with two apertures for receiving the ends of the cord, and a clip portion for clamping the tag.

In practice, one end of the cord is secured in the fastener before it leaves the 70 factory. When the fastener is applied to an object, it is then merely necessary to affix the free end of the cord in the fastener. This is done by passing the tip vertically through the aperture into the hollow interior of the fastener where it will, of its own accord, assume a horizontal position 75 crosswise of the aperture, as shown in Fig. 1, and thus preventing withdrawal.

What I claim as my invention and desire 80 to secure by Letters Patent is:

1. In a tag fastener, a hollow casing having a pair of spaced apertures in one end thereof, a flexible tie having a tip at each end secured thereto at points between the 85 tip ends, said tips in one position being receivable with the tie through the respective apertures and said casing being formed so as to prevent access to either tip or removal of the tie except by disrupting the 90 tie or the casing, and a tag carried by the casing.

2. In a tag fastener, a casing formed of a piece of metal bent into approximately 95 U-form and having a pair of spaced apertures along the line of bend and having the space between the walls of the casing along the sides thereof partly closed, a flexible tie having a tip secured to each end at points between the tip ends, said tips being receivable in one position through the respective apertures, and a tag received between the walls of the casing and being rigidly secured thereto so as to prevent access to the 100 tips or removal of the tie except by disrupting the casing or the tie.

3. In a tag fastener, a hollow casing having a pair of spaced apertures in one end thereof, a flexible tie having a tip at each end secured thereto at points between the 110

tip ends, said tips in one position being receivable with the tie through the respective apertures and said casing being formed so as to prevent access to either tip or removal of the tie except by disrupting the tie or the casing, and a tag secured to the opposite end of the casing and projecting outwardly therefrom.

4. In a tag fastener, a hollow casing having a pair of spaced apertures in one end thereof, a flexible tie having a tip at each

end secured thereto at points between the tip ends, said tips in one position being receivable with the tie through the respective apertures and said casing being formed so as to prevent access to either tip or removal of the tie except by disrupting the tie or the casing, said casing having a pair of spaced members at its opposite end, and a tag received in the space between said members and rigidly secured thereto.

MARCUS B. BEHRMAN.
